UNITED STATES PATENT OFFICE.

HENRY TIDEMAN, OF MENOMINEE, MICHIGAN.

TELEPHONE ANNUNCIATOR AND JACK.

No. 904,903.

Specification of Letters Patent. Patented Nov. 24, 1908.

Application filed July 6, 1907. Serial No. 382,425.

To all whom it may concern:

Be it known that I, HENRY TIDEMAN, a citizen of the United States of America, and a resident of Menominee, county of Menominee, State of Michigan, have invented 5 a new and useful Improvement in a Telephone Annunciator and Jack, of which the following is a specification.

My invention pertains to switch board 10 drops and has as its object the provision of a readily removable armature and helix for such a drop.

I provide an armature hung on journals, one of the journals being attached to the 15 armature by screw threads and having means whereby it may be withdrawn. The journal bearings in which these journals turn are slotted, and by withdrawing the removable journal, the armature may be 20 moved from the drop. I further provide simple connective means between the drop terminals and jack terminals.

In the drawings, Figure 1 shows side elevation of my combined drop and jack, Fig. 25 2 shows rear elevation, Fig. 3 shows section on broken line 3 of Fig. 2, Fig. 4 shows section through the journal of the armature, Fig. 5 shows same with armature in process 30 of removal, and Fig. 6 shows armature and journal boxes in perspective, separated.

On the drop shell 10, I mount the journal plate 11 which sustains the armature 12. The armature 12 has a transverse pin projecting as a journal bearing at 13, and has a 35 threaded stud at 14, the threaded stud being provided with a bushing or washer at 14'. The journal 15 has shoulder 16 and knurl 17 and has internal threads to screw upon the threaded stud 14. The armature 12, with 40 the journal 15 withdrawn, may be inserted in journal plate 11 through the slots 16, 16', but when the journal 15 is screwed into place, as shown in Fig. 4, the armature may 45 not be removed. The journal plate 11 is secured to the shell 10 by screws 18, passing through slots 19, whereby the adjustment of the armature to the core 20 may be obtained, and fixed by locking the screws 18, after

which the adjustment will not be disturbed by removing and replacing the armature 12. 50 Within the shell 10, I provide a fixed core 20 upon which mounts a helix in the removable spool 21. Upon the head of the spool 21 are conducting studs 22, 23, and upon the switch springs which normally 55 would be connected to the helix are similar conducting studs 24, 25. Conducting links 26, 27 connect the switch spring studs and helix studs as shown. The armature 12 is perforated for clearance of the studs 22, 23. 60 For removal of the helix from the drop, the screws of the four studs are loosened, the links are swung outward, as shown at 26', and the armature may be removed as above 65 described, permitting the removal and replacing of helix, after which the armature and links are replaced and the assembly of the drop is completed and in its original adjustment.

Having thus described my invention, what 70 I claim as new and desire to secure by United States Letters Patent is:

1. In a switchboard drop, an armature having a journal shaft integral therewith: slotted journal bearings for said journal shaft; and a sleeve for said journal shaft, 75 said sleeve being of greater diameter than the width of the slot of the journal bearing, and being attachable after said journal shaft is within said journal bearing, substantially 80 as described.

2. In a switchboard drop, a slotted journal bearing; an armature having a threaded journal shaft smaller than the journal bearing; and a threaded sleeve for said shaft and 85 having a journal bearing surface, said sleeve being removable from its position to permit removal of said shaft from said bearing, substantially as described.

Signed by me at Menominee, county of 90 Menominee and State of Michigan, in the presence of two witnesses.

HENRY TIDEMAN.

Witnesses:

LEOPOLD JACKMAN,
F. J. DONOVAN.
